UNITED STATES PATENT OFFICE.

MATHIAS F. MACNELLY, OF BUFFALO, NEW YORK, ASSIGNOR OF ONE-HALF TO OLIVER R. VASBINDER, OF BUFFALO, NEW YORK.

FASTENING DEVICE.

No. 873,063.

Specification of Letters Patent.

Patented Dec. 10, 1907.

Application filed March 31, 1906. Serial No. 309,214.

To all whom it may concern:

Be it known that I, MATHIAS F. MACNELLY, a citizen of the United States, residing at Buffalo, in the county of Erie and State of New York, have invented certain new and useful Improvements in Fastening Devices, of which the following is a specification.

This invention relates to fastening devices for garments, and other articles.

10 The primary object of my invention is the production of a simple fastening-device for closing the placket of a skirt. Although especially designed for such purpose, it is adapted for use wherever two flexible or 15 yielding parts are connected, or where an opening is to be closed by drawing the flexible walls of material together, as for example, in shoes, mail-bags, pockets, and the like.

Further objects are to provide the edges of 20 the material, or walls, as the case may be, with flexible enlargements, and apply thereto flexibly-connected runner-clasps or retainers capable of being moved along the flexible enlargements by a continuous movement in either direction to open and close the placket or opening; to provide two-part retainers and arrange them slidably on the edge of the material forming the placket or opening; to provide a fastening-device capable of closing or opening the placket with one 25 continuous movement and embodying in its construction, means for retaining the fastening-device in its closed condition; and to otherwise improve on devices of the type mentioned.

With these objects in view, the invention consists in the construction, arrangement, and combination of parts to be hereinafter described and particularly pointed out in the 30 appended claims.

In the drawings,—Figure 1 is an elevation of that portion of a lady's skirt containing the placket, the fastening-device being applied thereto and closing the placket. Fig. 2 is a similar view showing my improved fastening-device drawn down along the placket to permit the skirt to be opened. Fig. 3 is a vertical section taken on line $w-w$, Fig. 1. Fig. 4 is a vertical section taken on line $x-x$, Fig. 2. Fig. 5 is an inner view of that portion of a skirt containing my fastening-device, the latter being shown at full length to close the placket. Fig. 6 is a similar view showing the fastening-device drawn down to 35 open the placket. Fig. 7 is a perspective

view of the connecting portion of the device removed from the skirt. Fig. 8 is a sectional view taken on a plane indicated by line $y-y$, Fig. 3. Fig. 9 is an enlarged section taken on line $z-z$, Fig. 8. Fig. 10 is an enlarged perspective view of one of the retainers and a portion of the tape by means of which the retainers are flexibly connected. Fig. 11 is a perspective view of a retainer separated.

Referring to the drawings in detail, like numerals of reference refer to like parts in the several figures.

The reference numeral 1 designates a portion of a skirt having the belt thereof provided with a suitable belt-clasp 2 equipped at its lower end with a hook 3.

4 designates the placket or opening in the skirt, for the closing and opening of which my improved fastening-device 5 is designed. Secured to or in the skirt is a support 6, having sewed within its edge a flexible cord 7 to provide an enlargement at the edge of the placket or opening.

The connecting-portion of the fastening-device is designated by the numeral 8, and at 80 its upper end has secured a loop 9 adapted to engage the hook at the lower end of the belt-clasp 2.

Metallic retainers 10 are arranged slidably on the corded edge of the placket, each retainer comprising two connected parts 11 and 12 having flat contacting intermediate portions 13, and concaved ends 14 adapted to fit the corded edges of the placket; one of said parts having apertured lugs 15 through 85 which a flexible tape 16 is passed—which serves as a flexible connection between the several retainers. The apertured lugs are bent onto the sides of the other parts of the retainers and in addition to clamping the 90 flexible tape to the retainers also serve to secure the two parts of the retainers together. The uppermost retainer is by preference made wider than the remaining retainers and provided with a loop 18, to which is connected the loop 9 for connection with the belt-clasp. Sewed onto the flexible tape 16 is a flexible strip or tape 19, and in order to provide an even and finished exterior, a facing strip 20 is tacked to strip 19, which facing-strip may be of the same material from 100 which the skirt is made.

The retainers are moved along the corded edge of the placket by grasping the loop 9 and drawing upward or downward on the 110

latter. The fastening-device when drawn down will permit the opening of the skirt, as clearly shown in Figs. 2, 4, and 6.

When the loop 9 is engaged with the hook 5 of the belt-clasp, the device is retained against movement. By reason of the metallic retainers being separated, no inconvenience will be noticed when in sitting posture; the device conforming itself to any condition, and hanging gracefully with the lines of the skirt.

Although herein shown as in use on a lady's skirt, the device may be applied to various other articles, and changes in the 15 form, construction and arrangement of parts may be resorted to without departing from the spirit of my invention or sacrificing any of the advantages thereof.

Having thus described my invention, what 20 I claim is,—

1. A fastening-device consisting of a flexible support and metallic retainers secured to said support, each retainer comprising two parts having flat contacting intermediate 25 portions and opposing concaved end portions, one part of each retainer having lugs bent over the edges of the other part to secure said parts together.

2. A fastening device for closing openings or connecting two parts or articles, consisting of metallic retainers comprising two parts and held slidably to the edges of said opening, parts, or articles, one part of each retainer having lugs bent over the other part, and a flexible element clamped between the 35 two parts of each retainer.

3. A fastening-device consisting of a flexible support and metallic retainers, each retainer comprising two parts having flat contacting intermediate portions and opposing 40 concaved end portions, one part of each retainer having apertured lugs extending laterally from the edges of its flat intermediate portions and through the apertures of which said support is passed, said lugs being bent 45 over the edges of the other part of the retainers to clamp said support thereto and to secure the two parts of each retainer together.

In testimony whereof, I have affixed my 50 signature in the presence of two subscribing witnesses.
